UNITED STATES PATENT OFFICE

167,211

AIRPLANE

Conrad Warren Huffman, Big Bear Lake, Calif.

Application August 14, 1950, Serial No. 11,747

Term of patent 7 years

(Cl. D71—1)

To all whom it may concern:

Be it known that I, C. Warren Huffman, a citizen of the United States, residing at Big Bear Lake, in the county of San Bernardino and State of California, have invented a new, original, and ornamental Design for an Airplane, of which the following is a specification, reference being had to the accompanying drawing, forming part thereof.

In the drawing:

Fig. 1 is a top plan view of an airplane, showing my new design;

Fig. 2 is a side elevation thereof;

Fig. 3 is a front elevation; and

Fig. 4 is a perspective view.

I claim:

The ornamental design for an airplane, as shown.

C. WARREN HUFFMAN.
